UNITED STATES PATENT OFFICE

CHARLES A. EARLEY, OF DORCHESTER, MASSACHUSETTS

CAP FOR FLASHING

Application filed December 26, 1931. Serial No. 583,219.

This invention relates to improvements in sheet metal flashing, and particularly to a cap therefor.

The object of the invention is to provide a cap for a strip of flashing, the latter being of a type such as is inserted in the binding material of a wall between courses of masonry and utilized to form a waterproof cut-off course and the cap being utilized to form 10 a drain above the flashing through the binding material to the exterior of the wall.

The invention consists in a cap for flashing as set forth in the following specification and particularly as pointed out in the claims 15 thereof.

Referring to the drawing:—

Fig. 1 represents a plan view of a cap for flashing embodying my invention.

Fig. 2 is a vertical section through the wall 20 of a building illustrating my improved cap, together with the flashing with which it is associated inserted between courses of masonry at several locations upon said wall.

Fig. 3 is an enlarged sectional view through 25 a portion of a wall taken transversely of the cap at a location intermediate the transverse arches and at a position upon the wall as indicated by the lines 3—3 of Fig. 2.

Fig. 4 is a view similar to Fig. 3 but is 30 taken transversely of the cap in a plane in which the transverse arches thereof are located.

Fig. 5 is a sectional view through a portion 35 of the wall upon the longitudinal median line of the cap.

Like numerals refer to like parts throughout the several views of the drawing.

In the drawing, 6 represents a cap, preferably constructed of pressed sheet metal 40 and embodying therein oppositely disposed flat marginal portions 7 which extend longitudinally of the cap in the same plane, and an arch portion 8 which is interposed between the marginal portions 7 and also extends longitudinally of the cap. At one end of the cap the arch portion is curved downwardly at 9.

Also embodied in the cap 6 are a plurality 50 of other arch portions 10 which extend transversely across the marginal portions 7 upon

opposite sides of the arch 8 and intersect said last-named arch. When the cap 6 is placed upon a strip of flashing a passage 11, constituting a drain, is formed between the arch 8 and the flashing, and other passages 12 are 55 also formed between the arches 10 and the flashing, and these last-named passages all communicate with the passage 11.

In Fig. 2 I have illustrated a conventional form of wall in which strips of flashing of 60 any suitable form having caps 6 embodying my invention resting thereon are positioned at locations indicated at A, B and C. The wall embodies therein a coping 13 and a plurality of courses of brick 14, all of which are 65 joined together in a well-known manner by a suitable binding material 15. A strip of flashing 16 is inserted at A in the binding material 15 between the coping 13 and the uppermost layer of brick 14, and caps 6 embodying my invention are placed at regular intervals along the strip of flashing 16 and extend transversely thereacross.

During the construction of the wall, after 75 the caps 6 have been placed in position upon the strip of flashing, both flashing and cap are covered with a layer of the binding material, and it is evident that the cap 6 will act to hold the binding material that is located thereabove spaced apart from the 80 flashing, and a passage constituting a drain will be provided beneath the arch 8, which will extend entirely across the wall, and at the location A the passage 11 may drain both at the front and rear faces of the wall. The 85 flashing itself forms a waterproof cut-off course between the course of masonry located thereabove and therebelow and water which may collect upon said flashing will be conducted to the exterior of the wall by means 90 of the several drains.

At the location B upon the wall, a strip of flashing 17 provided with a downwardly turned flange 18 is located, but as this flashing is located above a roof 21, the caps 6 of 95 this invention may be placed in exactly the same manner as previously described in connection with the flashing 16, and the passage-way 11 beneath the arch 8 may drain at either the front or rear faces of the wall. 100

At the location C, which is at a position upon the wall above a window and below the roof 21, a strip of flashing 19 has an upwardly bent flange 20 embodied therein and as moisture often collects above the flashing between the inner face of the flange 20 and the adjacent face of the wall, it is desirable that said moisture shall be discharged at the front of the wall. In this case the caps 6 of my invention rest upon the flashing 19 extending transversely thereof, and the rear end of the cap abuts against the upturned flange 20 and communicates with any space that there may be between said flange and the wall in such a manner that moisture collecting in said space will flow through the passage 11 and be discharged at the front of the wall. The transverse passages 12 are provided for the purpose of enabling the moisture which may collect upon the strips of flashing to communicate with the main passage 11 beneath the caps. The curved end portion 9 of the cap preferably projects a slight distance outwardly beyond the face of the wall and acts to prevent water which may run down the wall, or be driven thereagainst by the wind, from entering the outlet of the drain.

I claim:

30 1. A cap of the character described comprising a strip of sheet material having an arch portion embodied therein and extending longitudinally thereof, and a plurality of other arch portions extending transversely of said strip and intersecting said longitudinal arch.

40 2. A cap of the character described comprising a strip of sheet material having flat marginal portions embodied therein and extending longitudinally thereof, an arch portion also extending longitudinally of said strip between said marginal portions, and a plurality of other arch portions extending transversely across said marginal portions

45 and intersecting said longitudinal arch.

50 3. In a masonry wall the combination with a strip of flashing and layer of binding material thereon of a cap resting upon said flashing and extending thereacross, said cap having an arch portion embodied therein extending transversely of said wall and holding the binding material thereabove spaced apart from the flashing, whereby a drain is formed beneath the arch communicating with the exterior of the wall.

55 4. In a masonry wall the combination with a strip of flashing and layer of binding material thereon of a cap resting upon said flashing and extending thereacross, said cap having flat marginal portions and an intermediate arch portion embodied therein extending transversely of said wall and holding the binding material thereabove spaced apart from the flashing, whereby a drain is formed

beneath the arch communicating with the exterior of the wall.

5. In a masonry wall the combination with a strip of flashing and layer of binding material thereon of a cap resting upon said flashing and extending thereacross, said cap having flat marginal portions and an intermediate arch portion embodied therein extending transversely of said wall, and a plurality of other arch portions intersecting said first-named arch portion whereby a drain is formed communicating with the exterior of the wall.

In testimony whereof I have hereunto set my hand.
